(57) **CLAIM**

We claim the ornamental design for a pan of a feeder assembly, as shown and described.

DESCRIPTION

FIG. 1 is a perspective view of the pan of a feeder assembly of our design;

FIG. 2 a top plan view of the pan of a feeder assembly of our design;

FIG. 3 is a bottom plan view of the pan of a feeder assembly of our design;

FIG. 4 is a front elevation view of the pan of a feeder assembly of our design, a rear elevation view not being shown as it is identical to the front elevation view; and,

FIG. 5 is a right side elevation view of the pan of a feeder assembly of our design, a left side elevation view being a mirror image thereof.
